DESIGN FOR A BROOCH OR THE LIKE

Thomas S. Themelis, New York, N. Y.

Application January 27, 1941, Serial No. 98,399

Term of patent 3½ years

To all whom it may concern:

Be it known that I, Thomas S. Themelis, a citizen of the United States and resident of New York city, in the county of New York and State of New York, have invented a new, original, and ornamental Design for a Brooch or the like, of which the following is a specification, reference being had to the accompanying drawing, forming a part thereof.

Fig. 1 is a top plan view of a brooch or the like, showing my new design.

Fig. 2 is a side elevational view of the same.

I claim:

The ornamental design for a brooch or the like, as shown.

THOMAS S. THEMELIS.
